UNITED STATES PATENT OFFICE.

ARTHUR E. CASE, OF MARION, INDIANA, ASSIGNOR TO DELTA ELECTRIC COMPANY, OF MARION, INDIANA, A CORPORATION OF INDIANA.

PORTABLE ELECTRIC LAMP.

Application filed April 30, 1920. Serial No. 377,748.

To all whom it may concern:

Be it known that I, ARTHUR E. CASE, a citizen of the United States, and a resident of Marion, in the county of Grant and State 5 of Indiana, have invented certain new and useful Improvements in Portable Electric Lamps, of which the following is a full, clear, and exact description.

The invention relates to portable electric 10 or flash lamps.

The objects of the invention are to provide; an improved switching device which is applicable either to a case made of conducting or non-conducting material; improved means located in a removable cap at the end for containing one of the members 15 of the switch; improved means for yieldingly locking the movable switch-member in closed or open position; improved means for 20 securing a switch member in the removable cap; and a portable electric lamp which is simple in construction and efficient in operation.

The invention consists in the several novel 25 features hereinafter set forth and more particularly defined by claims at the conclusion hereof.

In the drawings: Fig. 1 is a side elevation of a lamp embodying the invention. Fig. 30 2 is a longitudinal section, the battery and incandescent lamp being shown in elevation. Fig. 3 is a longitudinal section upon an enlarged scale through the cap and lower portion of the case. Fig. 4 is a plan of the cap. 35 Fig. 5 is a detail of the ring which is fixed in the lower end of the case to guide the end of the movable switch-member. Fig. 6 is a detail section on line 6—6 of Fig. 4. Fig. 7 is a detail section on line 7—7 of Fig. 40 1. Fig. 8 is a detail of the incandescent lamp socket.

The lamp comprises a cylindrical case 8 which may be either of insulating or conducting material and is adapted to contain 45 a battery 9 of usual construction, one end of the batteries being provided with a terminal 10 which is adapted to engage the tip-contact 11 of an incandescent lamp 12 which is provided with the usual screw-threaded base 50 13. A screw-threaded ring 14 is secured to the upper end of the body 8 by rivets 15. A hood 16 is screw-threaded to engage the ring 14 and thereby removably connected to the body. This hood is adapted to contain 55 a sheet-metal reflector 17. The upper end

of the hood 16 is screw-threaded, as at 18, to a ring 19 which is adapted to removably secure the lens or glass plate 20 and the reflector 17 in connected relation to the hood 16, the margins of the lens and the reflector 60 being clamped between the upper end of the hood and an inwardly extending flange 21 or ring 19. A lamp-socket 22 is riveted to the reflector and the base 13 of the lamp 12 is held in said socket. This lamp socket is 65 split, as at 22, to render it resilient so it will frictionally hold the lamp-base in desired position. This is important, because it becomes possible to focus the lamp with respect to the reflector. A conductor strip 23 70 is secured and electrically connected to the ring 14.

The lower end of the case 8 is adapted to be closed by a cap 25 which is provided with a screw-thread 26 to engage a corresponding thread 27 on a ring 28 which is secured to the lower end of case 8 by rivets 29. This cap is removable so that the battery may be inserted into and withdrawn from the body. A disk 30 of insulating material is 80 secured in the lower end of the cap 25 by a central hollow rivet 31. The margin 32 of the disk 30 engages the inner face of the end of the cap 25 and its central portion 33 is offset relatively to the margin so that it 85 will be spaced from the end of the cap. A contact-plate 34 is secured against the upper face of the insulating disk 30 by struck-up tongues 35 which pass through slots 36 in, and are clinched under, the insulating 90 disk to secure said disk and plate rigidly together. A coil-spring 37 is secured to the disk 34, the coil at one end being extended through eyes 38 struck up from the disk. The upper end of the spring is adapted to 95 bear against the electrode at the lower end of the battery 9 to serve as a conductor between the battery and plate 34, as well as to press the battery upward to maintain electrical contact between electrode 10 and contact 11. Plate 34, insulating disk 30 and spring 37, thus secured together, form an assembled unit which will be secured as an entity in the cap 25 by a rivet 31 which passes through a central hole in the cap and 100 in insulating disk 30. Plate 34 is provided with a rim or flange 39 with which the movable switch member is adapted to engage.

A finger-piece 40 is slidable on the outside of the case. An escutcheon plate 41 is 110

secured to the body by rivets 42. A slot 43 is formed in the body of the case and the escutcheon plate. A movable switch strip 44 has an offset portion 46 which is disposed in the slot 43 and is secured by rivets 45 to the finger-piece 40. A plate 40' is interposed between strip 44 and piece 40. This switch strip 44 is extended downwardly to the lower end of the case to engage the flange 39 of the plate 34. The lower end of this switch strip is guided into and out of engagement with said plate by a ferrule 50 which is secured in ring 28 and is fixed in the lower end of the case 8 and provided with an in-struck loop 51, the switch-strip passing between the loop and the wall of the ferrule. The lower end of the strip is provided with an offset terminal 52 and an offset portion 53 which are spaced apart a sufficient distance to receive the loop 51 when the switch is open, as shown in Fig. 2. The switch-strip is resilient and when the circuit is to be closed it is forced downwardly to bring the offset 53 below the loop 51 so that the switch-strip will be yieldingly locked in closed position. When the switch is open, it will also be yieldingly locked by offset portions 52 and 53 above and below the loop 51. This construction exemplifies a switch which is simple and whereby the circuit will be kept either open or closed without likelihood of accidental shift.

When the switch strip 44 is lowered, a circuit for the operation of the lamp will be established as follows: electrode 10, tip-contact 11, the filament of lamp 12, lamp-base 13, socket 22, reflector 17, hood 16, ring 14, rivet 24, strip 23, rivet 42, escutcheon plate 41, finger-piece 40, switch-strip 44, plate 34, spring 37 and the electrode at the lower end of the battery 9. When the switch-strip 44 is separated from the plate 34, the circuit will be interrupted between said parts. When the switch-strip is in position to open the circuit, its lower end will lie close to the wall of the case, so that the removal and insertion of the battery will not be interfered with.

The invention exemplifies a portable electric lamp which is simple in construction, can be produced at a low cost, which is adapted either for a case of insulating or conducting material and in which the switch is efficiently held in desired position.

The invention is not to be understood as restricted to the details set forth, since these may be modified within the scope of the appended claims, without departing from the spirit and scope of the invention.

60 I claim:

1. In a portable lamp, the combination of a case, a battery in the case, a switch, a reflector, an electric lamp, and a socket having one of its ends continuous and fixedly 65 and directly secured to the reflector and

through which the lamp-base is adapted to enter the socket, provided with a screw-thread for the lamp-base and having its other end split to hold the lamp in assigned focal relation to the reflector by the inherent 70 resiliency of the split end, the end of the socket secured in the reflector being inelastic.

2. In a portable lamp, the combination of a case, a battery in the case, a switch, a reflector, an electric lamp, and a socket having 75 a groove in its outer periphery in which the inner margin of the reflector is fixedly secured, provided with a screw-thread for the lamp-base, and having its other end split to hold the lamp in assigned focal relation to the reflector by its inherent resiliency, the grooved end of the socket being inelastic and the lamp-base being adapted to enter the socket through the inelastic end.

3. In a portable lamp, the combination of 85 a battery, a case containing the battery, a lamp held in one end of the case and in engagement with one terminal of the battery, a removable cap for the other end of the case, a contact-plate secured in the cap 90 and insulated therefrom, a switch strip slidably mounted in the case, and a ring in the case provided with a struck-up loop in which the strip is guided.

4. In a portable lamp, the combination of 95 a battery, a case containing the battery, a lamp held in one end of the case and in engagement with one terminal of the battery, a removable cap for the other end of the case, a contact-plate secured to the cap 100 and insulated therefrom, a switch-strip slidably mounted in the case, and a loop in one end of the case adjacent the cap in which said strip is guided, said strip being provided with an offset portion adapted to pass 105 through said loop.

5. In a portable lamp, the combination of 110 a battery, a case containing the battery, a lamp held in one end of the case and in engagement with one terminal of the battery, a removable cap for the other end of the case, a contact-plate secured in the cap and insulated therefrom, a switch-strip slidably mounted in the case, and means in one end of the case adjacent the cap to guide said 115 strip, said strip being provided with offset portions adapted to engage the guide means and for holding it in different positions.

6. In a portable lamp, the combination of 120 a battery, a case containing the battery, a lamp held in one end of the case and in engagement with one terminal of the battery, a removable cap for the other end of the case, a contact plate secured in the cap and insulated therefrom, a switch-strip slidably mounted in the case, and a loop in one end of the case adjacent the cap, in which said 125 strip is guided, said strip being provided with offset portions, one of which is adapted to pass through said loop.

7. In a portable lamp, the combination of a battery, a case containing the battery, a lamp held in one end of the case and in engagement with one terminal of the battery, a removable cap for the other end of the case, a contact-plate in the cap, an insulating disk between the plate and the cap having its central portion spaced away from the cap, a rivet extending through the cap and said insulating disk, means for securing the plate and insulating disk together and extending into the space between the disk and the cap, and a movable switch-strip in the case adapted to engage said plate.
- 5 10 15 20 25
8. In a portable lamp, the combination of a battery, a case containing the battery, a lamp held in one end of the case and in engagement with one terminal of the battery, a removable cap for the other end of the case, a contact plate in the cap, an insulating disk between the plate and the cap having an offset portion near its margin and its central portion spaced from the cap, means extending through the cap and said insulating disk, means for securing the plate and the central portion of the insulating disk together, the contact plate having a portion lapping the offset portion of the disk and a movable switch-strip in the case and adapted to engage said plate.

ARTHUR E. CASE.
